Patented Jan. 15, 1918.

UNITED STATES PATENT OFFICE.

PHILIP J. AHLERS, OF NEW YORK, N. Y.

PUTTEE.

1,253,557.

Specification of Letters Patent. Patented Jan. 15, 1918.

Application filed November 12, 1917. Serial No. 201,603.

To all whom it may concern:

Be it known that I, PHILIP J. AHLERS, a citizen of the United States, residing at borough of Manhattan, city, county, and State of New York, have invented a certain new and useful Improved Puttee, of which the following is a full, clear, and exact description.

My invention relates to puttees.

10 Among the principal objects which the present invention has in view are: to provide a puttee resilient in character throughout, and which can be used for either leg; to avoid constricting the part of the body to 15 which the puttee is applied; to provide a puttee which will conform to the shape of the leg to constitute an even covering therefor; to permit reversing the puttee for maintaining the appearance of cleanliness; to 20 augment the warmth of the puttee without increasing the weight.

The following is a description of a puttee embodying my invention, reference being had to the accompanying drawing, in 25 which:

Figure 1 is a face view of a puttee strip constructed and arranged in accordance with the present invention;

Fig. 2 is a detail view on an enlarged 30 scale, partly in section, to show the construction of the puttee;

Fig. 3 is a cross-section of the puttee on an enlarged scale, the section being taken as on the line 3—3, in Fig. 2;

35 Fig. 4 is a view showing the method of applying the puttee in service.

Heretofore puttees have been made from leather and from strips of single ply cloth of suitable character, the edges whereof 40 have been hemmed or otherwise formed to prevent raveling, the hemming or forming referred to having had the effect of rendering the edges of the puttee strip non-stretchable. The result has been that the leather 45 puttee unless shaped has formed a rough lapped edge of the article when in service, and the cloth material, the center of which has stretched more or less, has had the effect of binding on the non-stretchable edge 50 sections, so that the puttee has contracted on the leg and has interfered with the circulation of the blood therein. Again, when the puttee has become wet and subsequently

dried, the cloth or leather from which it has been constructed has contracted beyond 55 the original dimensions and has resulted in binding the leg too closely, requiring the wearer to suffer the inconvenience caused thereby or to readjust the puttees.

When constructed in the form in the present invention, the puttee consists primarily of a knitted, tubular strip 9. The strip is cut to the required length and at one extremity the end is turned in and secured by stitching. The end of the strip 9 that 60 is held by the stitching 10, as shown best in Fig. 2 of the drawings, is preferably squared. The opposite end of the puttee to which is attached the securing strap 11 is turned in and shaped to form the tapered 65 end section 12 the end of the strap 11 extending between the sides thereof so that the junction of said strap and body portion 70 present the same appearance on both sides of the body portion. The portions of the 75 strip that are turned in at this end are securely held by the stitching 13.

The strap 11 is constructed from tape or other suitable material which is non-stretchable. This strap is used for binding the top 80 portion of the puttee and is handled in the manner usual to the adjustment of puttees in service.

It will be observed that the tubular strip 9 is held by the stitching 10 and 13 in a 85 double ply, flattened condition, but the edges of the flattened strip thus formed, while they do not ravel, have the same resiliency or stretch as is given to the body. This admits 90 of the strip shaping itself to conform to the shape of the leg of the wearer and avoids in service any tendency to constrict or impede the circulation. It is obvious, also, that if a puttee thus constructed becomes damp, it 95 will not bind the leg of the wearer when drying, as the body and edges of the puttee will stretch to accommodate the strains due to the contraction in drying. On account of its resiliency, it can be used for either leg.

100 It is obvious that the material from which the puttee is constructed may be rendered impervious to water in many ways.

What I claim is:

1. As an article of manufacture, a puttee 105 having a resilient tubular body portion.

2. As an article of manufacture, a puttee having a knitted tubular body portion.
3. As an article of manufacture, a puttee having a knitted tubular body portion, the ends whereof are inturned and permanently held, one of the inturned end portions being tapered; and a securing strap constructed

of non-resilient material fixedly attached to the tapered end portion and between the sides thereof, the junction of said strap and said body portion being so joined as to present the same appearance on both sides of the body portion. 10

PHILIP J. AHLERS.
